JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

COMBINED LOOPER AND FEEDING MECHANISM FOR SEWING-MACHINES.

1,327,647.

Specification of Letters Patent.

Patented Jan. 13, 1920.

Application filed December 21, 1917, Serial No. 208,216. Renewed October 28, 1919. Serial No. 334,096.

To all whom it may concern:

Be it known that I, JOHN P. WEIS, a citizen of the United States, residing at Nyack, in the county of Rockland and State of New York, have invented certain new and useful Improvements in Combined Looper and Feeding Mechanism for Sewing-Machines, of which the following is a specification.

This invention relates to differential feeding mechanism for sewing machines and while it is especially adapted for use in sewing machines such as shown in my copending application for sewing shoulder straps to undergarments, Serial No. 184,567, filed 10 August 6, 1917, it may be used in various types of special sewing machines and particularly in that class of machines having a post for supporting the work.

The object of the invention is the provision of an improved feeding mechanism embodying a very efficient differential feed mechanism in which the height of both the main and differential feeds may be readily adjusted, and in which also the main feeds 20 may be independently adjusted with respect to the differential feed both vertically and laterally, and I believe I am the first to provide a gang differential feed for sewing machines whereby the differential feed can be manipulated while the machine is in operation to vary the feeding stroke of the feed dogs.

In the drawings accompanying and forming a part of this specification,

Figure 1 is an end view of so much of a sewing machine as is deemed necessary to illustrate this improvement, the cloth plate or post portion of the machine being in section clearly to show the feeding mechanism; 35 Fig. 2 is a top plan partly sectional view of the improvement; Fig. 3 is a front partly sectional view looking in the direction of the arrow in Fig. 1; Fig. 4 is a perspective detail view of the holder for the feed dogs; 40 Fig. 5 is a perspective view of the differential sliding dog; Fig. 6 is a detail side view of one of the main feed dogs; Fig. 7 is a perspective detail view of one part of the differential feed dog slide block; Fig. 8 is a 45 perspective detail view of the two differential feed dog slide blocks in position ready to be inserted in the holder; Fig. 9 is a view showing the actuating means for the differential and main feed dogs, also a portion of the looper actuating mechanism; and Fig. 50

10 is a perspective detail view of the main shaft stitch regulating disk, looper operating and feed lift eccentric.

Similar characters of reference indicate corresponding parts in the several figures of 60 the drawing.

In the preferred form thereof the bed plate 1 of the machine is provided with an upright post or cloth plate 2. The bed plate carries spaced bearings 2' for the bottom shaft 65 3, which rotates therein. An eccentric 4 (see Fig. 10) is secured to the end of the shaft adjacent one of the bearings 2' and has integral therewith a disk 5 provided with a T-shaped slot 6 for the adjustable stitch 70 regulating means generally indicated by 7, which comprises the collar screw 8 for adjusting the crank pin 9 to and from the center to vary the stroke of the connection or link 10 carried by the crank pin 9. The 75 other end of this connection or link 10 is connected, as at 11, to and between a pair of arms 12 by a pin 13 (see Fig. 3). These arms 12 are hung from and supported by a shaft 14 carried by spaced bearings 15—15 80 formed as a part of the post 2 forming the housing for the mechanism. To the hub 17 of the arms 12 an upwardly extending arm 18 is secured, the upper end of which also has a hub 19 for a pin 20. This pin connects 85 arms 21 and 22 to this hub, and to the opposite ends of these arms 21 and 22 is connected, as at 23, the feed dog carrier or holder 25. This feed dog holder (see Fig. 4) is provided with opposed dove-tail grooves 90 26 to receive a pair of dove-tail slide blocks 27—27. These blocks are tapped at 28 to receive screws 29 for securing thereto the differential feed dog 30. (Fig. 5). The slide blocks 27 are also provided with depending portions 32 which fit against the walls 33 of the opening 34 of the holder 25 so that when the blocks 27 slide in the dove-tail groove, they will be guided by the dove-tails as well as the depending portions thereof. The slide blocks 27 are made as two parts for convenience of manufacture so that the slot 35 can be milled therein without difficulty. This slot 35 provides a socket for the rounded end 36 of the actuating 105 lever 37, which gives movement to the slide block and differential feed dogs 30 relatively to the holder 25. This lever 37 is pivotally supported at 38 to bearings 39 carried by the post. The curved extending arm 110

40 of this lever 37 is provided with tapped holes to receive screws 41 and 41' which limit the movement of a slide block 42 which operates on the curved arm. The slide block 5 42 may be shifted up and down the arm by a rod 43 connected thereto as at 44 and a spring 45 connected to a link 46, which is attached at one end to the block 42 for operating the arm 40 and lever 37 to give movement to the differential feed dog, the opposite end of the spring being connected in such a way as to return the parts to the position shown in Fig. 1 after the rod 43 10 has been manipulated by a floor treadle 47 or its equivalent, a knee shift. The lever 46 has its hub 48 connected to the pin 13 between the two arms 12 so that the link 46 will be reciprocated and by reason of its connection with the slide block 42 and the curved arm 40, the lever 37 will rock on its shaft 38 so that the rounded end 36 will 15 give feeding movement to the differential feed dog 30. The feed dog carrier 25 is provided with a depending lug 42^a drilled to receive a pin 43^a for the attachment of a yoked coupling 44^a, which is tapped to receive the threaded connection 46^a provided with a lock nut 47. The other end 48^a of this connection is tapped into a similar yoke 25 20 and is also provided with a lock nut, so that vertical adjustment to regulate the height of the feed dogs with respect to the throat plate can be obtained. The yoke 49 is drilled to receive a pin 50 pivotally connecting this yoke to a lever 51 described hereinafter. The feed dog holder or carrier 25 is substantially U-shaped as at 52 (see Fig. 1), thereby providing free space for the operation of the loopers 53. The rear portion of the feed dog holder is provided with a lengthwise extending T-slot 54 for adjustably securing thereto several main feed dogs 58 (see Fig. 6). Each feed dog carries a nut 55 to fit the T-slot and is so shaped 25 as to clamp the feed dog in its proper vertical and lateral position, so as to properly coöperate with the throat plate 56 and presser foot 57 to properly feed the work. The feed dog 58 may be adjusted vertically 30 on its nut 55 by providing the dog with a slot 58' (shown in dotted lines), and the nut 55 may be adjusted laterally in the T-slot 54. In the present instance there are three feed dogs 58 secured in the T-slot (see Fig. 2). The eccentric 4 operates in the bearing 59 of the lever 51, which is yoked at 35 60 to straddle the lever 61 where it is pivotally connected to the lever 51 by a pin 62. A shaft 63 pivotally supports the lever 61 and is carried by a bearing on the post casing. The other arm 64 of the lever 61 terminates in a hub 65 drilled to receive a pin 66 and a link connection 67, the other end of which link is pivotally connected as 40 65 at 68 to the looper reciprocating yoke 69

(see Figs. 1 and 2). This yoke 69 is connected to two looper shafts 70 and 71 which oscillate therein. Means are provided to properly control the end movement of these looper shafts in the bearings of the yoke. 70 The shaft 70 operates in spaced bearings 72, while shaft 71 operates in spaced bearings 73. Carried by one looper shaft is a segmental gear 74 which meshes with a similar gear 75, carried by the other looper shaft, 75 so that each looper will have the same oscillating movement. Motion is transmitted to the shaft 70 by a rod connection 76 (see Fig. 3) and a ball socket 77 carried by a crank 78, which is secured to the shaft 70 80 (see Figs. 1 and 2) and this rod 76 may be operated from the driving shaft 3 in the manner shown in my pending application hereinafter referred to. In Fig. 1 the looper shaft 71 and the spaced supporting bearings 73 therefor are broken away to clearly show the connections of the looper mechanism. The two opposed independently mounted loopers 53 are supported on the shafts 70 and 71 for reciprocatory and oscillatory 85 movements to properly coöperate with the spaced sets of multiple needles 79. In the present improvement there are two sets of needles coöperating with the spaced loopers, also two thread carrying fingers 80, one 90 coöperating with each set of needles to form an ornamental stitch on top of the work while the loopers 53 form an ornamental stitch on the bottom of the work. Reference may be had to my contemporaneously pending application, Serial No. 184,567, filed August 6, 1917, for a more detailed description of this improved looper mechanism, needle mechanism and stitch carrying fingers, which are operative in the manner 95 therein shown and described. 100

The operation of these improved feeding and looper mechanisms is as follows: 105

The parts are so timed as to give endwise reciprocation to the link 10 to rock the arms 12 on their shaft 14. This rocks the arm 18 and gives endwise reciprocation to the feed dog holder or carrier 25 and at the same time the eccentric 4 operating in its bearing 59 operates lever 51 so as to give motion to 110 the feed dog holder or carrier by means of the adjustable yoke connection comprising parts 44^a, 46^a and 49^a thereby to give a rise and fall movement to the feed dogs and feed dog carrier so as to effect a four-motion feeding action to properly feed the work. The movement of the lever 51 also actuates the lever 61 on its shaft 63 to operate the arm 64 and reciprocate the link 67, and the yoke 69 therefor giving endwise reciprocation to 115 the looper shafts 70 and 71. Simultaneously with this movement the rod 76 is also actuated so as to rock the looper shafts by means of its connection 77 with the crank 78. The sliding feed dog 30 is moved at the same 120 125 130

time with the feed dogs 58 but the stroke of the feed may be varied by manipulating the slide block 42 up and down the curved arm 40. The link 46 has the same movement as the link 10 when the slide block is adjusted to the lowest position on the arm 40 so as to meet the bottom stop screw 41' (see Fig. 1). At this time the differential feed dog 30 will have the same movement as the feed dog 58, that is to say, they will feed in unison. On the other hand, when the slide block 42 returns to its initial or substantially its top position as shown in several views, the differential feed dog 30 will have a greater movement than the feed dog 58 to produce a gathering action on the work.

It will of course be understood that the various details may be more or less varied or departed from without changing the scope or spirit of the present improvement.

From the foregoing it will be observed that the looper mechanism includes a pair of spaced independently supported and opposed loopers located to operate in the space between the feed dog supporting portions of the feed dog carrier, and that a part of the looper actuating means is connected with the driving shaft through the medium of the same member or lever which gives the rise and fall movement to the feed dog carrier. It will also be observed that the actuating means for the differential feed dog is connected with the means which reciprocates the feed dog carrier, so that the differential feed dog may move in unison with the main feed dog when desired, and that during the operation of the feed mechanism the feeding movement of the differential feed dog may be varied at the will of the operator by merely shifting the block 42 on the curved arm 40, and therefore the present improvement provides a very efficient combined feeding and looper mechanism operated from the same driving shaft and largely from the same actuating means on that driving shaft.

The needle mechanism in the present instance, as shown in Fig. 3, comprises two sets of spaced needles 79, each set consisting of three needles while the finger mechanism comprises a pair of fingers 80, the needles being reciprocated by suitable means in the usual way, while the fingers are moved in a circular path substantially around the path of the needles by suitable mechanism, the details of which not being claimed herein, it is not necessary to further describe, since this operating means is described and claimed in my co-pending application hereinbefore referred to.

The present improved machine, being particularly constructed for a special character of work, this somewhat governs the form of the feed mechanism used. This special form of work also requires the use of

a post machine and as the working mechanism of the feeding and stitching elements must be confined in that post and as it is necessary to have access to these parts, it is therefore necessary to have both sides of the feed carrier open for the movement of the loopers, the handling of the thread and the threading of the loopers. As the top of the feeds must act through the slots in the throat plate to feed the work, there is only one position in which the U-shaped portion of the feed carrier can be located, and that is at the bottom thereof. If instead of this U-shaped feed carrier a one-sided feed carrier were used, this one-sided arrangement would not be practical because the opposite side of the feeds would sag out of level, permitting that side of the work handled by it to retard so that the feeding action on the goods would be distorted. If on the other hand, instead of a one-sided feed carrier a two-sided feed carrier were used with the bottom left open but suitably braced or yoked at the sides instead of at the bottom, there would be no way to thread the loopers or adjust them, neither would there be a satisfactory way of connecting the feed lifting connection 46a.

In the present machine, the feeding arrangement is such as to permit the work to be drawn in from the rear and feed off the machine. This necessitates that the major portion of the feed actuating mechanism be located at the front of the machine, which is a somewhat unusual arrangement in this type of machine. Further, since it is necessary to have the feed arranged as shown and to have a second feed operating on the goods in front of the needles and the main feed operating on the goods in the rear thereof, it follows that the needles descend into the U-shaped carrier, and in order to form the stitches the loopers must coöperate with the needles in that position, so that in the present improvement the U-shaped form of carrier is necessary to accomplish the object sought.

I claim as my invention:

1. A combined feed and looper mechanism comprising a substantially U-shaped feed dog carrier, means for imparting a rising and falling movement to the carrier, means for reciprocating the carrier, a looper having its axis located above the bottom of the U-shaped space of the feed dog carrier and within the space thereof and means, for actuating said looper.

2. A combined feed and looper mechanism comprising a substantially U-shaped feed dog carrier, means for imparting a rising and falling movement to the carrier, means for reciprocating the carrier, a plurality of independently supported loopers located within said carrier, and means for actuating said loopers.

3. A combined feed and looper mechanism comprising a substantially U-shaped feed dog carrier, means for imparting a rising and falling movement to the carrier, means for reciprocating the carrier, a plurality of independently supported oppositely movable loopers within said carrier, and means for operating said loopers.
4. A combined feed and looper mechanism comprising a substantially U-shaped feed dog carrier, means for imparting a four-motion movement to the carrier, a looper located within said carrier, a shaft for supporting it and extending into said U-shaped portion of the carrier, means for reciprocating the shaft, and means for oscillating it.
5. A combined feed and looper mechanism comprising a substantially U-shaped feed dog carrier, means for imparting a four-motion movement thereto, a pair of independently supported loopers located within said carrier, a pair of shafts for supporting said loopers, means for imparting endwise movement to the shafts, and means for oscillating said loopers.
6. A combined feed and looper mechanism comprising a substantially U-shaped feed dog carrier, means for imparting a four-motion movement thereto, a pair of independently supported loopers located within said carrier, a pair of shafts for supporting said loopers, means for imparting endwise movement to the shafts, means for oscillating said loopers and comprising means connected with one of said shafts, and means connecting said shafts for simultaneous movement.
7. A combined feed and looper mechanism comprising a substantially U-shaped feed dog carrier, means for imparting a four-motion movement thereto, a pair of independently supported loopers located within said carrier, a pair of shafts for supporting said loopers, means for imparting endwise movement to the shafts, means for oscillating said loopers and comprising means connected with one of said shafts, and means connecting said shafts for simultaneous movement, said means comprising gear mechanism.
8. A combined feed and looper mechanism comprising a substantially U-shaped feed dog carrier, a driving shaft, means operated thereby for imparting a four-motion movement to the carrier, a pair of independently supported loopers located within said carrier, a pair of shafts extending transversely to the driving shaft for supporting said loopers, and means operated from the driving shaft for imparting endwise movement to the shafts and oscillatory movement to the loopers.
9. A combined feed and looper mechanism comprising a substantially U-shaped feed dog carrier, a driving shaft, means operated thereby for imparting a four-motion movement to the carrier, a pair of independently supported loopers located within said carrier, a pair of shafts extending transversely to the driving shaft for supporting said loopers, and means operated from the driving shaft for imparting endwise movement to the shafts and oscillatory movement to the loopers.
10. A combined feed and looper mechanism comprising a substantially U-shaped feed dog carrier, means for imparting a four-motion movement thereto, a sliding feed dog carried by said carrier and movable in unison with said carrier, means for varying the movement of said sliding feed dog thereby to give a differential movement to the feed, and looper mechanism comprising a pair of shafts extending into the U-shaped portion of said carrier, loopers carried on the ends thereof, and actuating means for said loopers.
11. A combined feed and looper mechanism comprising a substantially U-shaped feed dog carrier, means for imparting a four-motion movement thereto, a sliding feed dog carried by said carrier and movable in unison with said carrier, means for varying the movement of said sliding feed dog to give a differential movement to the feed, looper mechanism including actuating means and loopers, each having its axis located above the bottom of the U-shaped space of the feed dog carrier and within the space thereof, and vertically and laterally adjustable main feed dogs also carried by said carrier.
12. A combined feed and looper mechanism comprising a substantially U-shaped feed dog carrier, means for imparting a four-motion movement thereto, a sliding feed dog carried by said carrier and movable in unison with said carrier, means for varying the movement of said sliding feed dog thereby to give a differential movement to the feed, looper mechanism comprising a pair of shafts extending into the U-shaped portion of the carrier, oppositely movable loopers carried on the ends thereof, actuating means for said loopers, and vertically and laterally adjustable main feed dogs also carried by said carrier, said sliding feed dog and main feed dog being located at the opposite sides of that part of the looper mechanism located within said carrier.
13. A combined feed and looper mechanism comprising a feed dog carrier having spaced supporting portions, feed dogs carried by said spaced supporting portions, means for imparting movement to said carrier, looper mechanism comprising a pair of

looper shafts extending into the space of said carrier, a pair of loopers carried on the ends of said shafts within said space, and means for oscillating and reciprocating said 5 loopers.

14. A combined feed and looper mechanism comprising a feed dog carrier having spaced supporting portions, feed dogs carried by said spaced supporting portions, 10 means for imparting movement to said carrier, looper mechanism comprising a pair of looper shafts extending into the space of said carrier, a pair of oppositely movable loopers carried on the ends of said shafts 15 within said space, and means for oscillating and reciprocating said loopers.

15. In a sewing machine having a driving shaft, the combination of a feed dog carrier, a lever system pivotally connected to said 20 carrier at one point and connecting it with the driving shaft for imparting a rising and falling movement to the carrier, a lever system connected to said carrier at another point and connecting it with the driving 25 shaft for imparting a backward and forward movement to said carrier, a differential feed dog carried by said carrier, a lever system connecting it with one of said lever systems for imparting a differential movement thereto and including a curved arm 30 and a sliding block, and means for adjusting said block at the will of the operator.

16. A combined feed and looper mechanism comprising a feed carrier having 35 spaced supporting portions, feed dogs carried by said spaced supporting portions, means for imparting a four-motion movement to said carrier, looper mechanism partly located within the space of said carrier, adjustable means for imparting a differential movement to one of said feed dogs and adjustable during the operation of the feed mechanism, and means for adjusting the carrier and its feed dogs.

45 17. A combined feed and looper mechanism comprising a feed carrier having spaced supporting portions, feed dogs carried by said spaced supporting portions, means for imparting a four-motion movement to said carrier, looper mechanism partly located within the space of said carrier, adjustable means for imparting a differential movement to one of said feed dogs and adjustable during the operation of the 50 feed mechanism, means for adjusting the carrier and its feed dogs, and means for adjusting the other feed dog laterally and vertically, relatively to its carrier.

55 18. A combined feed and looper mechanism comprising a feeder carrier having spaced supporting portions, feed dogs carried by said spaced supporting portions, means for imparting a four-motion movement to said carrier, looper mechanism 60 partly located within the space of said car-

rier, adjustable means for imparting a differential movement to one of said feed dogs and adjustable during the operation of the feed mechanism, means for adjusting the carrier and its feed dogs, means for adjusting 70 the other feed dog laterally and vertically relatively to its carrier, said looper mechanism comprising a pair of independently supported loopers, a shaft carrying each of said loopers, means for imparting 75 endwise movement to the shafts, means for rocking one of said shafts, and means connecting said shafts for simultaneous movement.

19. In a sewing machine, the combination 80 of a driving shaft, feed mechanism including a feed dog carrier, an actuating lever connected with the driving shaft, means pivotally connecting said carrier with and supporting it above said lever and driving 85 shaft for imparting a rising and falling movement to the carrier, a link also connected with the driving shaft, rocking arms connected with said link, and means connecting said rocking arms with said carrier for 90 reciprocating the carrier, the means for imparting rising and falling movement to and for reciprocating said carrier, all being located to one and the same side of said driving 95 shaft.

20. In a sewing machine, the combination of a driving shaft, feed mechanism including a feed dog carrier, an actuating lever connected with the driving shaft, adjustable means pivotally connecting said carrier with 100 and supporting it above said lever and driving shaft for imparting a rising and falling movement to the carrier, a link also connected with the driving shaft, rocking arms connected with said link, and means connecting said rocking arms with said carrier for reciprocating the carrier.

105 21. In a sewing machine, the combination of a driving shaft, feed mechanism comprising a substantially U-shaped feed dog carrier, an actuating lever connected with the driving shaft, means pivotally connecting said carrier with and supporting it above said lever for imparting a rising and falling movement to the carrier, a link also connected with the driving shaft, rocking arms connected with said link, means connecting said rocking arms with said carrier for reciprocating the carrier, a main feed dog carried by said carrier, a differential feed 110 dog also carried by said carrier, and means operative during the operation of the feed mechanism for varying the movement of said last feed dog.

115 120 22. In a sewing machine, the combination of a driving shaft, feed mechanism comprising a substantially U-shaped feed dog carrier, an actuating lever connected with the driving shaft, means pivotally connecting said carrier with and supporting it above 125 130

said lever for imparting a rising and falling movement to the carrier, a link also connected with the driving shaft, rocking arms connected with said link, means connecting 5 said rocking arms with said carrier for reciprocating the carrier, a main feed dog carried by said carrier, a differential feed dog also carried by said carrier, means operative during the operation of the feed 10 mechanism for varying the movement of said last feed dog and comprising an arm connected with said differential feed dog and having a curved portion, a block shiftable thereon and connected with said rocking arms, and means under the control of 15 the operator for shifting said block.

23. In a sewing machine, the combination of a driving shaft, feed mechanism comprising a substantially U-shaped feed dog carrier, an actuating lever connected with the driving shaft, means pivotally connecting said carrier with and supporting it above said lever for imparting a rising and falling movement to the carrier, a link also connected with the driving shaft, rocking arms connected with said last link, means connecting said rocking arms with said carrier for reciprocating the carrier, a main feed dog carried by said carrier, a differential feed 25 dog also carried by said carrier, means operative during the operation of the feed mechanism for varying the movement of said last feed dog and comprising an arm connected with said differential feed dog and having a curved portion, a block shiftable thereon and connected with said rocking arms, means under the control of the operator for shifting said block, looper mechanism comprising a pair of independently supported loopers located within said 30 U-shaped carrier, a pair of endwise movable shafts carrying said loopers, means for oscillating said shafts simultaneously, and means for shifting said shafts endwise and 35 connected with the lever to which the carrier is pivotally connected for rising and falling movement.

24. In a sewing machine having a driving shaft, the combination of a feed dog carrier, 50 a lever system pivotally connecting it at its underside with the driving shaft for imparting a rising and falling movement thereto, a lever system pivotally connecting the carrier at its forward side with said driving shaft for reciprocating it backward and forward, a differential feed dog carried by said carrier, a lever system connecting said dog with one of said lever systems for imparting 55 a differential movement thereto and including a curved arm and a sliding block thereon, and means adjustable at the will of the operator for shifting said block.

25. In a sewing machine having a driving shaft, the combination of a feed dog carrier, 60 a lever system pivotally connected to said

carrier at one point and connecting it with the driving shaft for imparting rising and falling movement to said carrier, a lever system connected to said carrier at another point and connecting it with the driving 70 shaft for reciprocating the carrier backward and forward, a differential feed dog carried by said carrier, a lever system connecting said dog with said last lever system for imparting a differential movement to the feed 75 dog and including a curved arm and a sliding block, and means connected with said block for adjusting said block at the will of the operator during the operation of the machine. 80

26. A feed mechanism for a sewing machine comprising a feed carrier having spaced supporting portions, feed dogs carried by said spaced supporting portions, a lever system for imparting a four-motion 85 movement to said carrier, adjustable means under the control of the operator for imparting a differential movement to one of said feed dogs and adjustable during the operation of the feed mechanism, and including a curved arm and a sliding block thereon also connected with said lever system, and means for adjusting the carrier and its feed dogs. 90

27. A feed mechanism for a sewing machine comprising a feed carrier having spaced supporting portions, feed dogs carried by said spaced supporting portions, means for imparting a four-motion movement to said carrier, adjustable means under the control of the operator for imparting a differential movement to one of said feed dogs and adjustable during the operation of the feed mechanism, and means for adjusting the carrier and its feed dogs, said 100 carrier being pivotally supported by its adjusting means. 105

28. In a sewing machine having a driving shaft, the combination of a feed dog carrier, a lever system pivotally connecting it at its 110 underside with said driving shaft for imparting a rising and falling movement to said carrier, a lever system pivotally connecting it at its forward side with said driving shaft for reciprocating the carrier 115 backward and forward, a differential feed dog carried by said carrier, a lever system pivotally connecting said feed dog with said last lever system and including a curved arm and a sliding block, the lever system 120 for reciprocating the feed dogs forward and backward and the lever system for shifting the differential feed dog having a common pivotal connection at one point, and means connected with said block for shifting 125 it at the will of the operator.

29. In a sewing machine having a driving shaft, the combination of a feed dog carrier, means connecting said carrier with the driving shaft for imparting rising and fall- 130

ing movement to the carrier, means connecting said carrier with the driving shaft for imparting forward and backward movement to the carrier, a differential feed dog carried by the carrier, means connecting said differential feed dog with one of the carrier actuating means and having a common pivotal connection therewith at one point and including a lever pivotally supported 5 between its ends to a fixed part of the machine and terminating below said pivotal support in a curved arm and a sliding block mounted thereon, and means for shifting said block at the will of the operator.

10 30. In a sewing machine having a driving shaft, the combination of a feed dog carrier, a lever system pivotally connecting it at one point with the driving shaft for imparting a rising and falling movement to the carrier, 20 a lever system connecting it at another point with the driving shaft for imparting a backward and forward movement to said carrier, a differential feed dog carried by said carrier, a lever system connecting it with one of said lever systems for imparting 25 a differential movement thereto and including a curved arm and a sliding block, means for adjusting said block at the will of the operator, said feed dog carrier comprising a pair of spaced feed dog supporting portions, a looper or loopers located within said space, a shaft for each of said loopers extending into said space, means connecting each of said shafts with the driving shaft for reciprocating each shaft, and means for oscillating the loopers.

30 31. In a sewing machine having a driving shaft, the combination of a feed dog carrier, a lever system pivotally connecting it at one point with the driving shaft for imparting rising and falling movement to said carrier, a lever system connecting said carrier at another point with the driving shaft for reciprocating the carrier backward and forward, 40 a differential feed dog carried by said carrier, a lever system connecting said dog with said last lever system for imparting a differential movement to the feed dog and including a curved arm and a sliding block, means 45 connected with said block for adjusting said block at the will of the operator, said feed dog carrier comprising a pair of spaced feed dog supporting portions, a looper or loopers located within said space, a shaft for each of said loopers extending into said space, means connecting each of said shafts with the driving shaft for reciprocating each shaft, and means for oscillating the loopers.

50 32. In a sewing machine having a driving shaft, the combination of a feed dog carrier, means connecting said carrier with the driving shaft for imparting rising and falling movement to the carrier, means connecting said carrier with the driving shaft for

50 imparting forward and backward movement to the carrier, a differential feed dog carried by the carrier, means connecting said differential feed dog with one of the carrier actuating means and having a common pivotal 70 connection therewith at one point and including a curved arm and a sliding block mounted thereon, means for shifting said block at the will of the operator, said feed dog carrier comprising a pair of spaced feed 75 dog supporting portions, a looper or loopers located within said space, a shaft for each of said loopers extending into said space, means connecting each of said shafts with the driving shaft for reciprocating each 80 shaft, and means for oscillating the loopers.

33. In a sewing machine, the combination of a driving shaft, actuating means connected therewith, feed mechanism comprising a feed dog carrier pivotally connected 85 with and directly above said actuating means for rising and falling movement, rocking means connected with the actuating means for reciprocating said carrier, a differential feed dog carried by said carrier, rocking 90 means also connected with said differential feed dog and having a curved arm, a member movable along said curved arm and also connected with said first rocking means and actuating means whereby the differential 95 feed dog may have a movement in unison with the feed dog carrier, and means connected with said movable member and under the control of the operator for varying the movement of said feed dog during the 100 operation of the feed mechanism.

34. In a sewing machine, the combination of a driving shaft, actuating means connected therewith, feed mechanism comprising a feed dog carrier pivotally connected 105 with and directly above said actuating means for rising and falling movement, rocking means connected with the actuating means for reciprocating said carrier, a differential feed dog carried by said carrier, 110 rocking means also connected with said differential feed dog and having a curved arm, a member movable along said curved arm and also connected with said first rocking means at a pivotal point of connection 115 whereby the differential feed dog may have a movement in unison with the feed dog carrier, and means connected with said movable member and under the control of the operator for varying the movement of said 120 feed dog during the operation of the feed mechanism.

35. In a sewing machine, the combination of a driving shaft, actuating means connected therewith, feed mechanism comprising a feed dog carrier pivotally connected 125 with and directly above said actuating means for rising and falling movement, rocking means connected with the actuating means for reciprocating said carrier, a 130

differential feed dog carried by said carrier, rocking means also connected with said differential feed dog and having a curved arm, a member movable along said curved arm 5 and also connected with said first rocking means and actuating means whereby the differential feed dog may have a movement in unison with the feed dog carrier, means connected with said movable member and under 10 the control of the operator for varying the movement of said feed dog during the operation of the feed mechanism, a main feed dog also carried by said carrier, and looper mechanism partly supported between said 15 differential feed dog and main feed dog.

36. In a sewing machine, the combination of a driving shaft, actuating means connected therewith, feed mechanism comprising a feed dog carrier pivotally connected 20 with and above said actuating means for rising and falling movement, rocking means connected with the actuating means for reciprocating said carrier, a differential feed dog carried by said carrier, rocking means 25 also connected with said differential feed dog and having a curved arm, a member movable along said curved arm and also connected with said first rocking means and actuating means whereby the differential 30 feed dog may have a movement in unison with the feed dog carrier, means connected with said movable member and under the control of the operator for varying the movement of said feed dog during the operation 35 of the feed mechanism, a main feed dog also carried by said carrier, looper mechanism partly supported between said differential feed dog and main feed dog and comprising a pair of independently supported loopers, parallelly located shafts for supporting 40 said loopers, means for connecting said shafts whereby both will have a simultaneous rocking movement, and means also connected 45 with a part of said actuating means for shifting said shafts lengthwise.

37. In a sewing machine, the combination of a driving shaft, actuating means connected therewith, a feed dog carrier pivotally supported above and connected with 50 said actuating means for rising and falling movement and adjustable relatively to said actuating means, a lever system connecting said actuating means with the feed dog carrier for reciprocating it, a main feed dog carried by the carrier, a differential feed dog carried by the carrier, a lever system also connected with the actuating means for shifting said differential feed dog, and means under 55 the control of the operator for varying the movement of said differential feed dog.

38. In a sewing machine, the combination of driving means, actuating means connected therewith, gang feeding means including a differential feed dog operatively 60

connected with said actuating means to impart to said gang feeding means a four-motion movement and a differential movement of the feed dog, means under the control of the operator and operative during 70 the movement of the feed mechanism for varying the movement of said differential feed dog, looper mechanism also connected with said actuating means and partly carried between said main and differential feed 75 dogs and comprising a pair of independently supported loopers, and lengthwise movable and oscillatory shafts for supporting said loopers.

39. A feed mechanism for a sewing machine comprising a feed dog carrier consisting of a pair of spaced supporting portions, one having dove-tailed ways in its upper side, a sliding block supported by 80 said dove-tailed ways, and a feed dog carried by said sliding block.

40. A feed mechanism for a sewing machine comprising a feed dog carrier consisting of a pair of spaced supporting portions, one having dove-tailed ways in its 85 upper side, a sliding block supported by said dove-tailed ways, and a feed dog carried by said sliding block, the other supporting portion of said carrier having a recess at its rear side for the reception of a main feed dog.

41. A feed mechanism for a sewing machine comprising a feed dog carrier consisting of a pair of spaced supporting portions, one having dove-tailed ways in its 90 top, a sliding block supported by said dove-tailed ways, and a feed dog carried by said sliding block, the other supporting portion of said carrier having a slot at its rear for the reception of one or more main feed 95 dogs.

42. A feed mechanism for a sewing machine comprising a feed dog carrier consisting of a pair of spaced supporting portions, one having a recess in its top face for the 100 reception of a sliding feed dog, and the other having a recess at its rear side for the reception of one or more feed dogs.

43. A feed mechanism for a sewing machine comprising a feed dog carrier consisting of a pair of spaced supporting portions, one having dove-tailed ways, a pair of members having registering recesses in their meeting faces and forming a sliding block located in said ways, a differential feed dog 115 carried by said sliding block, one or more main feed dogs carried by the other of said supporting portions, and operating means for said sliding block and having a part thereof projecting into said registering 120 recesses.

44. A feed mechanism for a sewing machine comprising a feed dog carrier consisting of a pair of spaced supporting portions, one having dove-tailed ways in its top, a 130

pair of recessed members forming a sliding block located in said ways, a differential feed dog carried by said sliding block, the other of said spaced supporting portions having a T-shaped slot at its rear, and one or more main feed dogs, each having a part projecting into said slot.

45. In a sewing machine, the combination of a driving shaft, actuating means connected therewith, a feed dog carrier comprising a pair of spaced supporting portions, one having a dove-tailed way, the other a T-shaped slot, an adjustable member pivotally connected with said actuating means and with the underside of said carrier for pivotally supporting it for rising and falling movement, rocking means pivotally connected with said carrier and with the actuating means for reciprocating said carrier, one or more main feed dogs carried by said T-shaped slot, a differential feed dog slidably supported by said dove-tailed way, rocking means connected with said differential feed dog and having a curved arm, a block movable on said curved arm and also connected with said first rocking means at its point of connection with the actuating means whereby the differential feed dog may have a movement in unison with the main feed dog, a spring for moving said block in one direction, and means under the control of the operator for moving the block in the opposite direction during the operation of the feed.

35 46. In a sewing machine, the combination of a driving shaft, actuating means connected therewith, a feed dog carrier comprising a pair of spaced supporting portions, one having a dove-tailed way, the other a T-shaped slot, an adjustable member pivotally connected with said actuating means and with the underside of said carrier for pivotally supporting it for rising and falling movement, rocking means pivotally connected with said carrier and with the actuating means for reciprocating said carrier, one or more main feed dogs carried by said T-shaped slot, a differential feed dog slidably supported by said dove-tailed way, rocking means connected with said differential feed dog and having a curved arm, a block movable on said curved arm and also connected with said first rocking means at its point of connection with the actuating means whereby the differential feed dog may have a movement in unison with the main feed dog, a spring for moving said block in one direction, means under the control of the operator for moving the block in the opposite direction during the operation of the feed, and looper mechanism also connected with that part of the actuating means which pivotally supports and imparts rising and falling movement to the carrier.

47. In a sewing machine, the combination of a driving shaft, actuating means connected therewith, a feed dog carrier comprising a pair of spaced supporting portions, one having a dove-tailed way, the other a T-shaped slot, an adjustable member pivotally connected with said actuating means and with the underside of said carrier for pivotally supporting it for rising and falling movement, rocking means pivotally connected with said carrier and with the actuating means for reciprocating said carrier, one or more main feed dogs carried by said T-shaped slot, a differential feed dog slidably supported by said dove-tailed way, rocking means connected with said differential feed dog and having a curved arm, a block movable on said curved arm and also connected with said first rocking means at its point of connection with the actuating means whereby the differential feed dog may have a movement in unison with the main feed dog, a spring for moving said block in one direction, means under the control of the operator for moving the block in the opposite direction during the operation of the feed, and looper mechanism also connected with that part of the actuating means which pivotally supports and imparts rising and falling movement to the carrier, a part of said looper mechanism being located between the spaced portions of the carrier.

48. In a sewing machine, the combination of a driving shaft, actuating means carried thereby, a feed dog carrier pivotally connected with said actuating means for rising and falling movement, means connecting said carrier with said actuating means for imparting a reciprocatory movement to the carrier, looper mechanism, and means supported independently of said actuating means and connecting said looper mechanism with that part of the actuating means which imparts rising and falling movement to the carrier.

49. In a sewing machine, the combination of a driving shaft, actuating means carried thereby, a feed dog carrier pivotally connected with said actuating means for rising and falling movement, means connecting said carrier with said actuating means for imparting a reciprocatory movement to the carrier, looper mechanism, means supported independently of said actuating means and connecting said looper mechanism with that part of the actuating means which imparts rising and falling movement to the carrier, said feed dog carrier comprising a pair of spaced supporting portions, feed dogs carried thereby, and said looper mechanism having a part thereof located in said spaced supporting portions.

50. In a sewing machine, the combination of a driving shaft, actuating means carried thereby, a feed dog carrier pivotally con-

nected with said actuating means for rising and falling movement, means connecting said carrier with said actuating means for imparting a reciprocatory movement to the carrier, looper mechanism, means connecting said looper mechanism with that part of the actuating means which imparts rising and falling movement to the carrier, said feed dog carrier comprising a pair of spaced supporting portions, feed dogs carried thereby, said looper mechanism having a part thereof located in said spaced supporting portions, means connecting one of said feed dogs with said actuating means, and means for varying the movement of said last feed dog.

51. In a sewing machine, the combination of a driving shaft, actuating means carried thereby, a feed dog carrier pivotally connected with said actuating means for rising and falling movement, means connecting said carrier with said actuating means for imparting a reciprocatory movement to the carrier, looper mechanism, means connecting said looper mechanism with that part of the actuating means which imparts rising and falling movement to the carrier, said feed dog carrier comprising a pair of spaced supporting portions, feed dogs carried thereby, said looper mechanism having a part thereof located in said spaced supporting portions, means connecting one of said feed dogs with said actuating means, means for varying the movement of said last feed dog and comprising a spring and means under the control of the operator during the operation of the feed mechanism.

52. In a sewing machine, the combination of two sets of spaced needles, a thread carrying finger coöperating with each set of needles, a gang feed including a differential feed dog, means for operating said gang feed, means for varying the movement of said differential feed dog and under the control of the operator during the operation of the feed mechanism, and looper mechanism comprising a pair of independently supported loopers and means for actuating said loopers, the organization being such that during the feeding movement of the work two rows of ornamental stitches are formed on the top and bottom of the work.

53. In a sewing machine, the combination

of two sets of spaced needles, a thread carrying finger coöperating with each set of needles, a gang feed including a differential feed dog, means for operating said gang feed, means for varying the movement of said differential feed dog and under the control of the operator during the operation of the feed mechanism, and looper mechanism comprising a pair of independently supported loopers and means for actuating said loopers, the organization being such that during the feeding movement of the work two rows of ornamental stitches are formed on the top and bottom of the work, said gang feed having feed dogs supported spaced apart and said loopers being located in the space between said feed dogs.

54. Feeding mechanism for a sewing machine comprising a main feed dog, a differential feed dog, means for actuating said feed dogs and including means for sliding the latter relatively to the former, means under the control of the operator and operative during the operation of the feed mechanism for varying the movement of said differential feed dog, looper mechanism comprising a plurality of independently supported loopers, and an upright post in which said feed mechanism, loopers and the major part of the actuating means are located.

55. Feeding mechanism for a sewing machine comprising a main feed dog, a differential feed dog, means for actuating said feed dogs and including means for sliding the latter relatively to the former, means under the control of the operator and operative during the operation of the feed mechanism for varying the movement of said differential feed dog, looper mechanism comprising a plurality of independently supported loopers, an upright post in which said feed mechanism, loopers and the major part of the actuating means are located, two sets of spaced needles, and thread carrying fingers coöperating therewith, the organization being such that during the feeding of the work two ornamental spaced rows of stitches are formed on the top and bottom of the work.

Signed at Nyack, Rockland county, New York, this 14th day of December, 1917.

JOHN P. WEIS.
